UNITED STATES PATENT OFFICE.

LLOYD NOTTINGHAM, OF PIKESVILLE, MARYLAND, ASSIGNOR OF ONE-HALF
TO SAMUEL H. BALLARD, OF BALTIMORE, MARYLAND.

TROUSERS-GUARD.

SPECIFICATION forming part of Letters Patent No. 633,889, dated September 26, 1899.

Application filed May 13, 1898. Serial No. 680,541. (No model.)

To all whom it may concern:

Be it known that I, LLOYD NOTTINGHAM, a citizen of the United States, residing at Pikesville, in the county of Baltimore and State of Maryland, have invented certain new and useful Improvements in Trouser-Guards, of which the following is a specification.

This invention relates to a combined guard and clamp for trousers.

10 The object of the invention is to provide a device that will serve, first, as a guard for the bottom of the trousers-legs at the heel, and, second, as a binder or clamp to confine the bottom of the trousers about the ankle, 15 as when it is desired to ride a bicycle.

The invention is illustrated in the accompanying drawings, in which—

Figure 1 is a view of the improved guard or clamp. Fig. 2 is a view of a leg of the 20 trousers, indicating the position of the guard or shield. Fig. 3 is a sectional view of a portion of the leg of a pair of trousers, showing the chain attached. Fig. 4 is a view showing the device holding the pants-leg folded 25 about the ankle.

The device consists of metal links in the form of a flat chain and a spring-clip at each end of the chain. The metal links *a* are connected and of such pattern as to lie flat.

30 The links may be graduated in size, the larger ones being at the middle and the smallest at each end. A spring-clip *b* has an eye *c*, which couples to the smallest link *a* at the end. One of these clips may be at each end. One of 35 these devices is to be attached to the bottom of each leg of the trousers on the inner

side and at the back or heel, as indicated by broken lines in Fig. 2, the chain being stretched to have a horizontal position.

The links may be attached to the cloth of 40 the trousers by any suitable means, such as a metal fastener or by needle and thread. Each link may be thus secured or as many of the links secured as desired. Thus attached the chain will lie flat like a braid against the 45 cloth of the trousers and will contact with the heel part of the shoe, and thereby serve as a guard or protector for the trousers. Also any link may be grasped by the clip *b* at either 50 end of the chain when the leg of the trousers is folded or gathered, as in Fig. 4, and then the chain will serve as a binder to hold the trousers close to the limb. Thus the device 55 serves a double purpose on the leg of the trousers.

Having thus described my invention, what I claim as new, and desire to secure by Letters Patent, is—

The combination with the legs of a pair of trousers of a flat flexible link-chain extending horizontally and attached to each leg of the trousers, and one or more spring-clips attached to the chain—said clips adapted to clamp any one link of the chain and bind or confine the bottom of the trousers about the 65 ankle of the wearer, as set forth.

In testimony whereof I affix my signature in the presence of two witnesses.

LLOYD NOTTINGHAM.
